UNITED STATES PATENT OFFICE

HEREWARD J. PEELE, OF ST. LOUIS, MISSOURI, ASSIGNOR TO S. G. ADAMS STAMP & STATIONERY COMPANY, OF ST. LOUIS, MISSOURI, A CORPORATION OF MISSOURI

INSIGNIA DEVICE

Application filed October 10, 1927. Serial No. 225,075.

This invention relates to insignia devices of various kinds and is herein illustrated as embodied in metal numerals such, for example, as those commonly employed for indicating the street number of a house.

Metal numerals as well as metal letters are employed in a variety of uses, and in order efficiently to perform their function it is necessary that their surfaces remain clear and distinct during use in order that they may be distinguished from a distance. It is common in the use of such devices to seat them firmly against a wall of a building or other structure and to secure them rigidly in their seated position. When so fastened they are subject to oxidation or similar defacement by reason of coming in contact with atmospheric moisture and, in the event that they are located out of doors, they are subject not only to rain that comes in direct contact with them but also rain and discolored matter contained in the support which accumulates and runs down over the face of the insignia devices.

A still further use to which devices of this character are commonly put consists in affixing them to telephone, telegraph or railway poles, and the like, to indicate the number of each pole or to indicate information pertaining to the attachments carried by the poles or other information of any kind, and when so used they are very likely to become obliterated owing to the fact that creosote or latex, with which poles are very often impregnated, exudes during warm weather and pours over the surface of the insignia devices. By treating the metal of the devices in such a way that it is rendered impervious to rust, many of the disadvantages mentioned above may be overcome, but there remains the danger of the insignia becoming partially or completely obliterated by the collection upon its outer surface of dirt and other matter which is washed thereon from the surface to which the insignia is affixed.

With the foregoing considerations in view the present invention has for an important object thereof the provision of an improved insignia device constructed in such a manner

that when affixed to a flat support it will stand outwardly therefrom in which position the surface of the insignia will be impassable by liquids flowing across the surface of the support.

55

A feature of the invention consists in providing a metal insignia with projections extending from the rear face of the insignia in such a manner that the projections will be the only parts of the insignia to contact with a support to which the insignia is affixed.

60

A further feature of the invention consists of pressing the projections out of the material of which the insignia is made. Forming the projections in this way permits the improved insignia to be manufactured economically and at substantially the cost of the ordinary insignia device.

65

Other features and objects of the invention will become apparent from a reading of the following description in the light of the accompanying drawings, in which:

70

Fig. 1 is a view in front elevation showing a metal numeral having the invention embodied therein,

75

Fig. 2 is a plan view in section taken along line 2—2 of Fig. 1,

80

Fig. 3 is a view similar to Fig. 1 showing a modified form of the invention,

Fig. 4 is a plan view in section taken along line 4—4 of Fig. 3, and

85

Figs. 5, 6, 7, 8 and 9 are each views in perspective showing modifications of the invention.

85

As shown in the drawings the reference numeral 10 indicates a vertical support, such, for example, as a house front, telephone pole, etc., to which there is affixed by means of nails 12, or other similar fastenings, the metal insignia 14 shown in Figs. 1 to 5 inclusive herein, in the form of a numeral seven.

90

As shown in Fig. 1 and 2, the insignia 14 is provided with a plurality of semi-spherical projections 16 extending rearwardly from the insignia, and it is to be observed that the projections are so arranged and spaced that when the insignia is affixed to

95

100

the support only the projections will be in contact with the support.

While the projections have been illustrated in Figs. 1 and 2 of the drawings as comprising a semi-spherical shape, it is to be understood that the invention contemplates the employment of other forms of projections, as, for example, that illustrated in Figs. 3 and 4 in which triangular projections are stamped out of the metal to extend rearwardly of the insignia 14; Fig. 5 in which the insignia is provided with counter-sunk depressions 20 having openings 22 for receiving the fastenings 12 formed at the bottom of the depressions; Fig. 6 in which counter-sunk depressions are of a sufficiently small diameter that large heads 24 of the fastenings may rest upon the surface of the insignia adjacent to the depressions; Fig. 7 in which rectangular projections 26 are pressed rearwardly out of the metal of the insignia; Fig. 8 in which an elongated groove or depression 28 is provided at its bottom with openings 30 for receiving the fastenings 12; and Fig. 9 in which a V-shaped groove is pressed in the insignia.

It is to be appreciated that all of the various modified forms of the invention efficiently carry out the idea of affixing the insignia to a support in such a manner that it will extend outwardly therefrom, and it is also to be realized that still further modifications may be provided without departing from the spirit and scope of the invention.

As shown in the drawings the depressions or projections are located in most instances in close proximity to the holes in the insignia through which pass the fastenings. The purpose in this arrangement consists in providing the metal surrounding the openings for the fastenings with an abutment or a firm backing in order that the heads of the fastenings will firmly engage the metal surface of the insignia without bending or otherwise causing distortion of the metal.

Having thus described my invention, which I claim as new and desire to secure by Letters Patent of the United States is:

1. A metal insignia comprising a one-piece, stamped out member shaped to the desired form, a hollow extension on said member to space same from the element by which it is supported, said extension being arranged in contact with said support and being provided with an aperture formed in a wall thereof, a headed fastening device extended through said aperture and into said support to secure the insignia to the support, the entire head portion of said fastening device including the outer face thereof of being spaced inwardly of the outer surface of the insignia.

2. A metal insignia comprising a one-piece, stamped out member shaped to the desired form, said member having a depressed portion to provide an integrally formed hollow extension to space said member from the element by which it is supported, said extension being arranged in contact with said support and being provided with an aperture formed in a wall thereof, and a headed fastening device extended through said aperture and into said support to secure the insignia to the support, the entire head portion of said fastening device including the outer face thereof of being spaced inwardly of the outer surface of the insignia.

In testimony that I claim the foregoing I hereunto affix my signature.

HEREWARD J. PEELE.
